UNITED STATES PATENT OFFICE.

JOHN A. CAMERON, OF MONROE, NEW YORK.

DESIGN FOR A MAIL BOX.

Application filed July 6, 1927. Serial No. 22,671. Term of patent 7 years.

To all whom it may concern:

Be it known that I, JOHN A. CAMERON, a citizen of the United States, residing in Monroe, county of Orange, in the State of New York, have invented a new, original, and ornamental Design for Mail Boxes, of which the following is a specification, reference being had to the accompanying drawings forming a part hereof, in which:

I claim:

The ornamental design for a mail box, as shown.

This specification signed this 1st day of July, A. D. 1927.

JOHN A. CAMERON.
